(57) **CLAIM**

The ornamental design for a film-transferring device for office-use, as shown and described.

DESCRIPTION

FIG. 1 is a top plan view of a film-transferring device for office use showing my new design;
FIG. 2 is a front elevational view thereof;
FIG. 3 is a left side elevational view thereof;
FIG. 4 is a right side elevational view thereof;
FIG. 5 is a bottom plan view thereof;
FIG. 6 is a rear elevational view thereof;
FIG. 7 is a bottom plan view of the body portion with the cap member removed for ease of illustration;
FIG. 8 is a rear elevational view of FIG. 7;
FIG. 9 is a top plan view of FIG. 7;
FIG. 10 is a front elevational view of FIG. 7;
FIG. 11 is a left side elevational view of FIG. 7;
FIG. 12 is a right side elevational view of FIG. 7;
FIG. 13 is a top plan view of the cap member shown separately for ease of illustration;
FIG. 14 is a front elevational view of FIG. 13;
FIG. 15 is a bottom plan view of FIG. 13;
FIG. 16 is a right side elevational view of FIG. 13;
FIG. 17 is a left side elevational view of FIG. 13;
FIG. 18 is a referential top plan view of FIG. 7;
FIG. 19 is a referential left side elevational view of FIG. 7;
FIG. 20 is a referential perspective view of FIG. 1;
FIG. 21 is a referential front elevational view of FIG. 2; and,
FIG. 22 is a cross-sectional view taken in the direction of arrows 22—22 in FIG. 21.
